UNITED STATES PATENT OFFICE.

WALTER A. LEIMER, OF DENVER, COLORADO.

KEY RING OR HOLDER.

1,172,374.

Specification of Letters Patent. Patented Feb. 22, 1916.

Application filed December 11, 1914. Serial No. 876,684.

To all whom it may concern:

Be it known that I, WALTER A. LEIMER, a citizen of the United States of America, residing in the city and county of Denver 5 and State of Colorado, have invented a new and useful Key Ring or Holder, of which the following is a specification.

My invention relates to a key ring or holder, and the object of my invention is to 10 provide a key holder with elongated parallel sides having an aperture cut in one side of sufficient size to allow keys being passed freely on the holder and to have this aperture closed by a movable hollow sleeve which 15 slides over the end, and upon being brought back into position, closes the aperture by engaging the other end of the holder, the sleeve being held in place by a flange which protrudes toward the center and fits into a 20 receiving groove or channel in this end of the holder, which end is split or divided for a short distance, longitudinally, allowing the ends so formed to be pressed together by the operator, and upon releasing the 25 same they assume their natural position, engaging the flange on the sleeve, thus securing the sleeve and making practically a solid ring. I attain this object by the mechanism 30 illustrated in the accompanying drawings, in which:

Figure 1 is a perspective view of the ring closed. Fig. 2 is a sectional view of the ring showing the sleeve "D" in position closing the ends and held in position by the flange "K" engaged in the receiving channels "H" of the spring members "J," this 35 end being cut out to form two spring members which can be pressed together to release or engage the sleeve when in position. 40 The flange "C" at the end "A" prevents the sleeve "D" from becoming entirely disengaged. Fig. 3 is an end view of the end J,

showing the tapering of the ends to allow them to pass freely into and out of the engaging flange in the sleeve. And Fig. 4 represents a view of the end J, showing the flange E and the receiving channel or groove H.

Similar letters of reference refer to similar parts throughout the several views. 50

Referring to the drawings my invention contemplates an improved key ring or holder which can be opened readily and have one key removed without removing the others, and when closed forming a practically solid 55 ring which will not become opened while in the pocket or out, without considerable pressure being exerted laterally upon the ends J and at the same time a pulling back 60 of the movable sleeve D which operates over the end A.

Having described my invention, what I claim as new and desire to secure by Letters Patent, is:

A key-ring or holder whose ends are in 65 alignment but spaced apart, in combination with a hollow sleeve member of even bore, containing flanges on its extremities, mounted to operate over one end of the ring and adapted to be moved across the aperture 70 between the ends and to close the ends of said ring, one end being divided to form two 75 spring members, each having a receiving channel to engage a flange on said movable sleeve member and tapered ends to said spring members to facilitate their connection with said sleeve member.

In testimony whereof, I affix my signature in the presence of two witnesses.

WALTER A. LEIMER.

Witnesses:

ADELLA M. FOWLE,
ELIZABETH SMITH.
